(57) **CLAIM**

(21) Appl. No.: **29/158,103**

The ornamental design for a liquid container and mounting strap, as shown and described.

(22) Filed: **Mar. 29, 2002**

DESCRIPTION

(51) LOC (7) Cl. **03-01**

FIG. 1 is a front elevational view of a liquid container and mounting strap showing my new design;

(52) U.S. Cl. **D3/229; D3/215**

FIG. 2 is a rear elevational view thereof;

(58) Field of Search D3/229, 202, 215,

FIG. 3 is a side view, taken from the left side of FIG. 1;

D3/228; 224/148.5, 148.7, 222, 219, 269,

FIG. 4 is a side view, taken from the right side of FIG. 1;

148.6, 148.4

FIG. 5 is a top plan view thereof;

FIG. 6 is a bottom plan view thereof; and,

FIG. 7 is a perspective view thereof.

The broken line showing an arm in FIG. 7 is for illustrative purposes only and forms no part of the claimed design.
